UNITED STATES PATENT OFFICE.

JAMES B. KIRBY, OF WEST RICHFIELD, OHIO.

IRONING MACHINE.

Application filed May 8, 1922. Serial No. 559,237.

To all whom it may concern:

Be it known that I, JAMES B. KIRBY, a citizen of the United States, residing at West Richfield, in the county of Summit and State of Ohio, have invented a certain new and useful Improvement in Ironing Machines, of which the following is a full, clear, and exact description, reference being had to the accompanying drawings.

10 This invention relates to ironing machines of the type designed primarily for domestic use and has for its main object the provision of a machine of maximum simplicity which shall perform the largest possible kinds of work with a minimum of effort or skill on the operator's part. Subsidiary objects of the invention are the provision of a machine wherein the movement and pressure of the ironing shoe are produced in a new way and by the action of the motor; the provision of a machine having plural speeds selectively usable; the provision of a new construction for securing an open ended device without structural weakness; the provision of simple control devices located at a plurality of points for effecting movement of the shoe and controlling the amount of such movement; the provision of new means for releasing the shoe in case the power fails; 20 while further objects and advantages of the invention will become apparent as the description proceeds.

One of the most salient features of the invention is the use of fluid pressure for effecting the operation and controlling the pressure of the same, this pressure being produced by a motor driven pump.

In the drawings accompanying and forming a part of this application I have shown one of the many physical structures in which my inventive idea can be embodied, this drawing being intended to be illustrative only and not limiting upon me. Fig. 1 is a front elevation of a complete ironing machine containing my invention; Figs. 2 and 3 are left and right end elevations, respectively, of the same machine; Fig. 4 represents a vertical section, corresponding to the line 4—4 of Fig. 2; Fig. 5 is a top plan view of the gear casing with the cover removed; Fig. 6 is a cross-sectional view corresponding to the line 6—6 of Fig. 1; Fig. 7 is a perspective view of the open end of

the machine; Fig. 8 is a perspective view of one of the cylinders and the distance controlling device; and Fig. 9 is a diagram of the pressure connections.

Describing by reference characters the parts herein shown 1 represents a suitable supporting frame having a horizontal feeding shelf 2 at the top and a horizontal receiving shelf 3 at a lower point. The upper shelf is supported from the lower shelf by means of standards 4—4 at the forward part of the frame, and pivoted at 5, 5 to 55 suitable standards 6, at the rearward part of said frame are the levers 7, 7 which carry the elongated ironing shoe 8 extending from end to end of the machine in rear of the feeding shelf 2. Journaled in the upright 6 60 at the left-hand end of the machine is the horizontal shaft 9 carrying the padded roll 10, its opposite end being journaled in a bracket 11 carried by the upright 4 at the right-hand end of the machine. This 70 bracket is offset a considerable distance from the plane of the upright 4, this upright being therefore displaced a corresponding distance inwardly from the end of the roll as shown in Figs. 1 and 7, while the shoe 7 75 extends to the end of the roll thereby producing an open ended machine which is particularly convenient for ironing cuffs, collars, skirt hems, and other articles which cannot conveniently be put through the 80 body of the machine. This bracket preferably projects substantially horizontally from the upright 4 as shown in Fig. 7 and the receiving shelf 3 is preferably projected 85 lengthwise a sufficient distance to catch articles ironed at that point.

Secured at the left-hand end of the machine is a casing member having at its upper part a hollow gear chamber 12 and having at its lower part a fluid-pressure reservoir 13, a pump cylinder 14, and a sump 15. The gear chamber 12 is traversed by a partition 16 and between said partition and the end of the casing opposite thereto are journaled a pair of parallel shafts 17 and 18, 90 respectively, the latter being aligned with the roll shaft 9. Rigidly secured to the end of the shaft 18 is one member 20 of a clutch, and slidably splined on the end of the shaft 9 is a clutch spool 21 cooperating therewith 95 and controlled by the pivoted lever 22 which

has one end extended as shown at 23 to a point where it can be engaged by a projection 24 carried by the shoe 8 in such wise that the clutch will be engaged when the 5 shoe is moved to within a predetermined distance of the roll 10, being disengaged by a suitable spring 25 whenever this distance is exceeded. Loosely journaled on the shaft 18 at the other side of the partition 16 are 10 two unequal sized spur gears 27 and 28, respectively, having clutch teeth 29-29 on their adjacent faces adapted to be engaged selectively by companion teeth carried by the slideable clutch spool 30, splined to said 15 shaft between them and moved by the yoke 31 controlled by the lever 32. The shaft 17 is located below the shaft 18 and carries rigid pinions 34-35 of unequal size meshing with the gears 27 and 28, respectively. 20 The inner end of the shaft 17 on the opposite side of the partition 16 is provided with a worm gear 36 carrying a wrist pin 37, which drives the pump plunger 38 by means of the pitman 39 and meshes with the worm 25 40 carried by the shaft of an electric motor 41 mounted on the shelf 42 at the rear of the casing.

Carried by the frame 1 below the shelf 3 are a pair of horizontal cylinders 45-45 30 having movable tightly fitting pistons 46 therein and piston rods 47 passing snugly through packing glands 48 and articulated by suitable links 49 to the lower end of the arms 7 which carry the shoe 8. The two 35 ends of these cylinders are connected by suitable pipes 50-51 with a two-way valve 52 which may be located at any convenient point on the machine but is here shown as carried by the top of the sump 15. One 40 port of this valve is connected to the sump and the other with the reservoir by the pipe 54. It will be seen that when the valve 52 is turned to one position the fluid pressure in the reservoir will actuate the pistons to 45 force the shoe against the roll, and when moved to the opposite position it will reverse such action drawing the shoe away from the roll. Also, inasmuch as it is not necessary to draw the shoe away with the 50 same force that it is pressed against the roll, the parts are so arranged that the withdrawing movement is produced by the pressure exerted upon that side of the piston which carries the piston-rod, and this rod 55 is made of such size as to reduce the effective area of the piston by a suitable degree.

For convenience in manipulating this valve with all types of work I have illustrated a rock shaft 56 as journaled in the uprights 4 beneath the feed shelf 2 and having at each end the hand levers 57-58, connection to the valve being effected by the arm 59 and link 60. With this arrangement it is possible for the operator while 60 using the middle part of the roll to control

the movement of the shoe by the use of either hand, and while using the open end of the roll to operate the shoe by the lever 58.

It is desirable to withdraw the shoe from the roll to different distances under different operating conditions: for example, it is sometimes desirable in feeding articles to the machine to retract the shoe momentarily a very small amount, for example, from a quarter to a half inch, to enable the insertion of the article to be ironed; at other times to effect a larger opening, either for the purpose of arranging the article or to prevent burning of the roll during a protracted wait; and on other occasions to effect an extreme opening in order to wax the shoe or for other purposes. It is also desirable not to effect an unduly great displacement at any time to avoid delay and one of the best modes in which this can be effected is as follows:

Pivoted to each of the levers 7 is a pawl 64 and carried by the machine frame is a stepped plate 65 co-operating therewith. In the present embodiment I have shown 90 this plate as constituting the base of the corresponding cylinder, the steps being so arranged as to arrest the rearward movement of the shoe at positions of one half inch, two inches, and six inches, or thereabout as may be desired. The face of the pawl is made wider than the face of the plate as shown in Fig. 8, and alongside each plate I locate a pivoted ramp 66 upon which the overhanging portion of the pawl may 95 rest. These ramps are rigidly secured to a suitable rock shaft 67 which extends from end to end of the machine, the free end of that ramp which is located at the right hand end of the machine being provided 100 with an out turned resilient arm 68 which projects through an arcuate slot 69 formed in the machine frame; and the free end of the other ramp being provided with an out-turned rigid arm 70 which projects 105 through an arcuate slot 71 in the opposite end member of the frame. One wall of the slot 69 is formed with serrations 72 into which the arm 68 will snap so as to hold the ramps at different heights, and the arm 70 is connected by means of the link 73 to the arm 74 of a hand lever 75 carried by the upright 4 at the left hand end of the machine so as to permit operation at this 110 point also. The serrations 72 are so formed that the arm 68 can be forced past the same by actuation of the lever 75 and are so designed in number and arrangement that the ramps 66 will cover one or more of the steps 65 depending upon the position of said arms. I have shown the lever 75 as loosely sleeved on the rock shaft 56 so as to be conveniently accessible, but any suitable arrangement can be employed.

The pump is of the common pressure or 130

force-pump type and needs no special explanation. It is preferably arranged to operate continuously during the running of the motor, but the sump is made of sufficient size to hold all the oil of the system, the reservoir being made of a somewhat greater size than the sump so as to hold the same amount of oil together with a quantity of air. Inside the chamber 12 the reservoir is provided with a relief valve 80, the movable part of which is controlled by a spring 82 adjustable by means of a screw 83. Of course it is not imperative to have this relief valve located at this point, but this arrangement is particularly desirable because of the fact that a certain amount of leakage is likely to occur at this valve and this arrangement avoids trouble therefrom because the entire bottom part of the casing 20 can be made leak-proof. Indeed leakage at this point is advantageous since it tends to maintain a layer of oil into which the pinions 34 and 35 may dip thereby lubricating the entire mechanism. An overflow port 84 is provided whereby the worm and worm gear are supplied, and any excess of oil therethrough or any leakage past the pump plunger is returned to the sump by way of the drain 85. This drain also constitutes the vent for the sump and an air inlet for maintaining an air supply in the reservoir.

The operation of the device is as follows—when the clutch lever 32 is in central position the motor can be operated without driving any part excepting the pump, and by actuating the levers 57 and 58 the shoe can be moved backwards and forwards as may be desired in pressing certain types of articles without rotating the roll. By throwing this clutch lever in one direction or the other the shaft 18 is driven at different speeds as may be required by different classes of work or by operators of varying dexterity. The lever 75 is normally kept in such position that the shoe will be moved away from the roll only the minimum distance, which is effected almost instantaneously by the stored up air pressure, but upon occasion the ramps may be raised to permit the removal of the shoe to such greater distance as may be desirable, and still returned by the mechanism without physical effort. The clutch lever 22—23 is so adjusted that the roll will be operated when the shoe is at or within the first step but stationary when outside of the first step. The pressure of the shoe against the roll is adjusted by turning the hand-wheel 83 in an obvious manner. In case a fuse should become blown out, the current fail, or the motor stop for any other reason, burning of the roll or of any articles being ironed is prevented by the manipulation of the valve 52 in the usual manner, the capac-

ity of the reservoir being sufficient to operate the shoe repeatedly after the motor has been cut off.

When the pump is made to run continuously as herein shown its capacity may be made very small. When the pump has drained all the oil out of the sump it will begin to pump air, although the pump clearance and valve arrangements are so chosen as to limit the maximum pressure at any desired point, this pressure therefore being the same regardless of the amount of oil in the machine. If at any time the amount of oil becomes too small a new supply is poured into the case, this alone serving for the entire lubrication of the machine excepting the roll shaft which is preferably mounted in roller bearings and needs no oiling.

It will be understood that I do not limit myself to the employment of air pressure, but claim the use of fluid pressure generally for the purpose described; for example oil pressure alone, the desired pressure adjustment being secured by spring pressed members cooperating therewith. Also that I do not restrict myself to a constantly running pump since the same can be arranged to work intermittently, either according to the requirement of operating the shoe, or according to the degree of pressure desired. Also that I do not restrict myself to the employment of a fluid-pressure-operating-mechanism in combination with this one type of roll and shoe, but may employ it in combination with any type of roll or heated member regardless how arranged and regardless which one is moved and which is fixed. Also that I do not limit myself to the particular form and arrangement of the controlling mechanism or to the arrangement of the gearing or to the number and location of the various cylinders and their co-operating parts or in any other manner excepting as specifically recited in the claims hereto annexed.

Having thus described my invention what I claim is:

1. In a self-contained, domestic ironing machine, a frame, a revoluble roller and a heated shoe carried thereby, said roller and shoe being movable one toward and from the other, in combination with fluid pressure means for effecting such movement and electrically operated means carried by said frame for driving said roller and for producing such fluid pressure.

2. In a self-contained, domestic ironing machine, in combination, a frame a roller and a heated shoe carried thereby, one movable toward and from the other, a motor carried by said frame for driving said roller, a fluid-pressure pump driven by said motor, and mechanism operable by such fluid pressure for effecting such movement.

3. In a self-contained, domestic ironing machine, in combination, a frame a roller and a heated shoe carried thereby, one movable toward and from the other, a fluid-pressure pump carried by said frame, power-means for driving said roller and operating said pump, mechanism operable by such fluid pressure for effecting such movement, and means for adjustably controlling such fluid pressure whereby the pressure of said roller against said heated member is regulated. 65
4. In an ironing machine, a roller and a heated member, one movable toward and from the other, a fluid pressure pump, power-means for driving said roller and pump, mechanism operable by such fluid pressure for effecting such movement, and means for arresting the separating movement of said member and roller at various predetermined points. 70
5. In a self-contained, domestic ironing machine, in combination, a frame a roller and a heated shoe carried thereby, one movable toward and from the other, a fluid-pressure pump carried by said frame, power-means for driving said roller and operating said pump, mechanism operable by such fluid pressure for effecting such movement, and controlling means operable from a plurality of different positions on said machine for controlling the time and direction of application of such fluid pressure to such mechanism. 75
6. In an ironing machine, a roller and a heated member, one movable toward and from the other, a fluid pressure pump, a motor continuously connected to said pump in driving relation, separable driving connections between said motor and roller, fluid-pressure-actuated mechanism for effecting the relative movement of said roller and heated member, manually operable devices for controlling the application of said fluid pressure to said mechanism, and automatically operated means for connecting said separable connections upon approaching movement of said heated member and roller and for disconnecting the same upon the reverse movement thereof. 80
7. In an ironing machine, a roller and a heated member, one movable toward and from the other, a liquid pressure pump, a motor operatively connected to said pump in driving relation, an air-pressure reservoir connected to said pump, a manually regulable pressure-controlling valve communicating with the bottom of said reservoir, fluid-pressure-actuated mechanism for effecting the relative movement of said roller and heated member, and manually operable devices for connecting said reservoir to said mechanism in either approaching or separating relation. 85
8. In an ironing machine, a roll and a shoe, one movable toward and from the other, liquid pressure devices for effecting such movement, and an air-chamber operatively connected with said liquid-pressure devices for maintaining the pressure elastic. 90
9. In an ironing machine, a roll and a shoe, one movable toward and from the other, piston and cylinder devices for effecting such movement, an air chamber and a liquid chamber carried by said machine, a pump connecting the bottom of said chambers, operative connections between the pump and the motor which operates the roll, and valve devices for connecting the bottom part of said air chamber to either end of the cylinder and piston devices and for venting the opposite end of the same to said liquid chamber. 95
10. In an ironing machine, in combination, a roll and a shoe, one movable toward and from the other, piston and cylinder devices for effecting such movement, a motor, driving connections between said motor and roll including a clutch, a pump connected to said motor independently of said clutch, a fluid pressure reservoir into which said pump delivers, manually controllable valves for connecting said reservoir to said piston and cylinder devices, and means operative by the movement so produced for operating said clutch. 100
11. In an ironing machine, in combination, a roller and a heated member, movable the one toward and from the other, and fluid pressure devices for effecting such movement, said devices comprising a reservoir, a sump, and a constantly running pump there-between, together with suitable cylinders and pistons, there being sufficient liquid in the system to fill said cylinders at least once and said reservoir and said sump being each of sufficient size to hold all the liquid in the system. 105
12. In an ironing machine, a roll and a shoe, one movable toward and from the other, piston and cylinder devices for effecting such movement, a motor, a selective speed gearing driven thereby, driving connections between said gearing and said roll, said connections including a clutch, manually controllable valves for such fluid pressure devices, and means operative by the movement so produced for operating said clutch. 110
13. In a self-contained, domestic ironing machine, in combination, a frame, a roll journaled therein, a shoe carried by said frame and movable toward and from said roll, a motor carried by said frame, an energy-storing device carried by said frame and operated by said motor, manually controllable means for connecting said device to said shoe to move the same toward and away from the roll by said stored energy, 115
- 120
- 125

and means for connecting said motor in driving relation to said roll.

14. In an ironing machine, in combination, a roll, a shoe movable toward and from the same, means for stopping the retreating movement of the shoe at a plurality of different points, and manually controllable, fluid pressure devices for moving said shoe toward and away from the roll within the limits established by said means.

15. In an ironing machine, a roll, a shoe, one movable toward and from the other, fluid pressure devices for effecting such movement and producing ironing pressure between said shoe and roll and pressing the same against the roll, means for adjusting such pressure, and manually controllable valves for governing the application of such fluid pressure.

16. In an ironing machine, a roll, a shoe, movable toward and from the same, a gear chamber, a pressure reservoir having a relief valve opening into said gear chamber, a motor, an oil pump driven thereby and connected to said reservoir, gearing in said chamber for connecting said motor to said roll, piston and cylinder devices operatively connected to said shoe in such wise as to move the same toward and from said roll, and manually operable valve devices for

controlling the admission of oil from said reservoir to said piston and cylinder devices.

17. In an ironing machine, in combination, a frame having at one end a pair of spaced uprights, a shoe carried by one upright, a feeding shelf rigidly attached to the other upright, and a roll journaled between said feeding shelf and shoe both said shoe and said roll projecting beyond said uprights and the journal device including an offset bracket secured to its upright at a point beneath said shelf and projecting laterally toward said shoe.

18. In an ironing machine, in combination, a frame having a pair of uprights, a horizontal feed shelf rigidly carried thereby, an offset bracket projecting laterally from one of said uprights at a point beneath said shelf and extending to a point removed beyond the end of its upright, a roll journaled to said bracket and to the other upright and having its top approximately level with the top of said shelf, and a shoe supported by said frame on the opposite side of said roll, and having a length substantially equal to that of the roll.

In testimony whereof, I hereunto affix my signature.

JAMES B. KIRBY.
